PUSH BENCH DRIVE

Sydney Smith, London, England, assignor to
 Wellman Seaver Rolling Mill Company Limited,
 London, England, a company of Great Britain

Application June 18, 1938, Serial No. 214,559
 In Great Britain June 21, 1937

8 Claims. (Cl. 205—4)

This invention relates to apparatus for the manufacture of metal tubes and other tubular metal articles.

The apparatus is of the push bench type by which a somewhat thick cup-shaped hollow billet carried on an end of a mandrel is pushed through dies or through passes between rolls which decrease successively in cross-sectional area in the forward direction, whereby the billet is reduced in thickness and spread out lengthwise along the mandrel until the billet is brought to or approximately to the form of a tube of the required thickness and length. An example of such apparatus is described in the specification 15 of British Letters Patent No. 300,288. The inner end of the mandrel is engaged with a mandrel carrier which in turn is carried or supported by a driving rack by which it and the mandrel are moved forward and retracted, the rack being driven by a driving pinion which in turn is operated by a driving motor. A large tube requires a greater pushing force to drive it through the dies than a smaller tube and consequently a smaller tube can be produced at a greater drawing speed than a larger tube. Further, as 25 it is usual to effect a greater reduction of cross-sectional area in the first or earlier dies than in the final or finishing dies a greater pushing force is required when the tube is being acted on by the first dies than when it is being acted on by the finishing dies alone.

The rate of output of a push-bench drawing apparatus in numbers of tubes of a given length per unit of time, for example one hour, depends, 35 for a particular size of tube largely on the rate at which the motor armature together with the moving parts of the push bench apparatus will accelerate to full speed and decelerate to rest in both the forward and return strokes of the rack.

Usually the driving motor is a direct current electric motor which drives the rack driving pinion through a reduction gear, a direct current motor being employed because it can be readily adjusted to the different speeds at which different sizes of tubes have to be produced on a single drawing apparatus and further it will give a high starting torque. Also a direct current motor will give a constant torque while accelerating to the normal forward or pushing speed of the rack, and during the return movement of the rack will operate at a higher maximum speed, usually double that required for the forward drive, and will provide a constant power output. As, however, the supply is usually al-

ternating current, a motor generator or other converting apparatus has to be included in the plant.

To drive the push bench apparatus, the motor has to be large so that in some cases the energy absorbed in accelerating the armature to its full speed may be from 4 to 6 times that required to accelerate and drive the other moving parts of the apparatus, that is from 75 to 85% of the power of the motor is absorbed in accelerating its armature. Thus the time of a pushing operation is dictated ultimately by the inertia of the motor armature. To provide the necessary torque for accelerating the armature and the moving parts of the bench, the motor 10 has to have a constant torque characteristic from rest to its maximum forward speed, whereas it would generally be preferable for the motor to provide a constant horse power.

The present invention has for object to provide driving means for push bench drawing apparatus in which inertia losses in the driving means are greatly reduced and consequently the size of the driving motor may be reduced, capital and maintenance costs will be reduced, shocks 25 transmitted to the tube being pushed will be reduced and a better tube will result, the output of the push bench will be increased, and the pushing speeds will be automatically reduced at high loads and increased at light loads, as with 30 different sizes of tubes, or with load variation during completion of the pushing stroke or should the material be hotter at one time than another.

The present invention comprises the combination with push bench drawing apparatus of driving means therefor comprising a driving motor, an hydraulic torque converter connected to said motor and a reversing gear connected between the output shaft of the converter and the moving element of the push bench apparatus. 35 In this combination, the torque converter permits of the use of a smaller motor, because it may be run at constant speed, eliminating the aforesaid problems of armature-inertia power-consumption. The motor need essentially be large enough 40 only to provide power for accelerating the parts beyond the converter. Owing to the presence of the said converter, extra power for accelerating the motor itself is not required and the motor may consequently be made of smaller size than 45 hitherto.

Further features of the invention will appear from the following description, by way of example, of an embodiment of the invention illustrated in the accompanying drawing, in which:

Fig. 1 is a plan view of driving means for a push-bench drawing apparatus,

Fig. 2 is a plan view of reversing gear to a larger scale, the cover of the gear having been 5 removed, and

Fig. 3 is a cross-section on the line III—III in Fig. 2.

Referring to Fig. 1, the driving means consists generally of an electric motor 1, an hydraulic 10 torque converter 2 and reversing gear 3 and a final gear drive 4. From the latter the usual rack 5, which moves the mandrel through the mandrel carrier, is driven through a pinion 6 or pinions.

15 The driving motor 1 may be either a direct current motor or an alternating current motor and, if the latter, is conveniently an induction motor.

20 The hydraulic torque converter 2 may be of any convenient known type. A satisfactory type consists essentially of a centrifugal pump, driven by the motor 1, which supplies liquid to a turbine whose rotor is connected to the shaft 8, and thus to the reversing gear 3. The blades 25 of the pump are adjustable to permit of variation of the speed of supply of the liquid to the turbine or of complete cutting off of the said supply. The blades may be adjusted manually, for example by the handle 7, or by means of 30 a servo-motor controlled, for example by a cam, so as to cause the speed of the output shaft 8 of the converter to follow a predetermined speed range. For instance, an example of a torque converter with adjustable blades is disclosed by

35 U. S. Patent No. 1,900,120 of March 7, 1933.

In the reversing gear illustrated in Fig. 2 the output shaft 8 of the converter is connected by reduction gearing 9 to a shaft 10 which, for the forward drive, can be coupled by a clutch 40 11 to a shaft 12 connected to the final drive 4. For the reverse drive, a shaft 13 connected to the shaft 10 through gear-wheels 14, 15 on the said shafts and an intermediate wheel 16 can be coupled by a clutch 17 to a gear-wheel 18 45 which is free on the shaft 13 and meshes with a gear-wheel 19 on the shaft 12. The movable parts of the clutches 11, 17, for instance coil clutches, are arranged to be operated by forks 20, 21 manipulated together from a handle 22. Between extreme positions in which one clutch 50 is engaged and the other disengaged there is an intermediate neutral position, shown in Fig. 2. With reversing gear of this kind, the reverse drive transmitted may have a higher ratio than the forward speed in any appropriate relation.

55 In the operation of the above-described driving means, the motor 1, when started, continues to run at a more or less constant speed. The speed of the output shaft 8, of the torque converter 2 automatically varies inversely as the power required in the operation of the push bench from instant to instant. Thus the speed of the shaft 8 increases as the power required by the rack 5 decreases and vice versa. The 60 clutches of the reversing gear are operated at the appropriate moments to cause the rack to travel forwards and rearwards.

To start a forward stroke of the rack 5, the clutch 11 is engaged while the torque converter 70 2 is in a condition of adjustment in which its output shaft 8 is stationary or substantially stationary, so that the clutch is engaged under light load conditions. After this engagement of the clutch 11, the torque converter is adjusted 75 so that power is transmitted to the shaft 8

and thence through the gearing 3, 4, 6 to the rack. The latter rapidly increases its speed, since the only parts to be accelerated, in addition to the said gearing, are the moving parts of the bench, i. e., parts on the output side of the torque converter. At the end of the forward stroke of the rack 5, the converter is adjusted so that its output side is allowed to slip in relation to the input side, that is to fall off in speed, whereupon the torque from the driving motor is destroyed almost immediately. Before the rack has come to rest at the end of the forward stroke, the clutch 11 is disengaged and the other clutch 17 is engaged. The torque converter is then adjusted so that power is again transmitted from the motor 1 to the output shaft 8, but in the opposite direction. Thus the rack and other moving parts of the bench may be arrested by using the converter as a brake until the inertia of the said parts is destroyed, whereupon the rack 20 will at once start its rearward stroke. A similar reversal is performed at the end of this stroke.

In some cases, it may be advisable to provide a flywheel between the motor 1 and torque converter 2 to ensure a smoother drive and also, possibly, to permit of a further reduction in the size of the motor.

To permit of a braking effect being exerted upon the rack independently of the braking effect which can be produced, as explained above, by the torque converter, a brake of appropriate type may be provided between the reversing gear 3 and the rack pinion 6.

Types of reversing gear other than that illustrated may be employed.

What I claim is:

1. The combination with the mandrel and reducing means of tube-making push-bench apparatus of driving means for driving the mandrel, on which the tube is formed, through the reducing means, comprising a driving motor, an hydraulic torque converter connected to the said motor, and a reversing gear connected between the output side of the converter and the moving element of the push-bench apparatus.

2. Driving means in accordance with claim 1, wherein the driving motor is an alternating current motor which runs at substantially constant speed, preferably an induction motor.

3. Driving means in accordance with claim 1, wherein the torque converter is of the type consisting essentially of a driven centrifugal pump and a driving turbine supplied with liquid by the pump whose blades are adjustable for controlling the supply of liquid to the turbine.

4. Driving means in accordance with claim 1, wherein a flywheel is arranged between the motor and torque converter.

5. Driving means in accordance with any one of the preceding claims, wherein the reversing gear is a clutch-controlled mechanical gear.

6. Driving arrangement for a tube-making push-bench apparatus comprising a driving motor, an hydraulic torque converter connected to the said motor and a reversing gear connected to the output side of the said converter.

7. In a tube making push bench apparatus wherein the mandrel is pushed forward by a reciprocating driving rack actuated on its forcing and return strokes by a meshing rotary pinion; a drive for said pinion including a rotary electric motor, an hydraulic torque converter connected with and driven by said motor, and mechanical reversing gear connected with and driven

by said converter and operatively coupled to said pinion for driving the same.

8. A tube making push bench apparatus including a mandrel forcing reciprocatory rack bar and its driving pinion, a drive for said pinion including a prime rotary motor, an hydraulic

torque converter operatively coupled to and driven by the motor, and mechanical reversing gear with controlling clutches operatively coupled to and driven by said converter and operatively coupled to said pinion for driving the same.

SYDNEY SMITH.
